UNITED STATES PATENT OFFICE

136,011

DESIGN FOR A BABY'S BASSINET AND TOILET STAND OR SIMILAR ARTICLE

Boyd A. Doty, Buffalo, N. Y., assignor to Hard
Manufacturing Company, Buffalo, N. Y.

Application March 5, 1943, Serial No. 109,674

Term of patent 14 years

To all whom it may concern:

Be it known that I, Boyd A. Doty, a citizen of the United States, residing at Buffalo, Erie County, State of New York, have invented a new, original, and ornamental Design for a Baby's Bassinet and Toilet Stand or Similar Article, of which the following is a specification, reference being had to the accompanying drawing, forming a part thereof.

In the drawing:

Fig. 1 is a perspective view of a baby's bassinet and toilet stand or similar article, showing my design, the shelf element being illustrated in its extended position.

Fig. 2 is a top plan view thereof.

Fig. 3 is a front elevational view thereof, the shelf element being illustrated in its retracted position.

Fig. 4 is a side elevational view thereof.

The dominant feature of my design resides in the stand portion illustrated in full lines in the drawing.

I claim:

The ornamental design for a baby's bassinet and toilet stand or similar article, substantially as shown and described.

BOYD A. DOTY.
